INVENTOR

Charles G. Hess,

BY. *O. M. Schell*

ATTORNEY

UNITED STATES PATENT OFFICE.

CHARLES G. HESS, OF FORT WORTH, TEXAS.

NOZZLE.

No. 914,490.

Specification of Letters Patent.

Patented March 9, 1909.

Application filed August 26, 1907. Serial No. 399,107.

To all whom it may concern:

Be it known that I, CHARLES G. HESS, citizen of the United States, residing at Fort Worth, in the county of Tarrant and State of Texas, have invented certain new and useful improvements in Nozzles, of which the following is a specification.

My invention relates to new and useful improvements in nozzles.

10 The object of the invention is to provide a nozzle having a novelly constructed valve arranged to be adjusted in conjunction with a cylindrical head to produce sprays of various degrees of fineness, a heavy or full stream, or a round stream such as is produced by the ordinary nozzle.

Another feature resides in the simple construction of the valve and its arrangement whereby it is readily seated by the pressure 20 of the liquid.

A still further object lies in the construction and the particular disposition of the spray opening whereby the nozzle when placed on the ground serves the purpose of a 25 lawn spray.

Finally the object of the invention is to provide a device of the character described that will be strong, durable, quick acting and convenient in use, comparatively inexpensive to produce, also one in which the parts 30 will not be liable to get out of working order.

With the above and other objects in view, the invention has particular relation to certain novel features, an example of which is described in the specification and illustrated 35 in the accompanying drawings, wherein:

Figure 1 is a vertical sectional view of the nozzle showing the valve in elevation, Fig. 2 is a vertical sectional view of the nozzle taken 40 at right angles to Fig. 1, Fig. 3 is an elevation of the nozzle, Fig. 4 is a partial vertical sectional view similar to Fig. 2 but showing the valve adjusted to a different position, Fig. 5 is a perspective view of the valve, and Fig. 6 is a perspective view of the nozzle 45 showing it in position for use as a lawn spray.

In the drawings, the numeral 1 designates a nozzle which is formed with a neck portion 2 which terminates in a cylindrical head 3, 50 lying at right angles thereto. At one side of the vertical center of the head an elongated rectangular spray opening 4 is provided. Within the head a cylindrical valve 5 is mounted to freely turn. The valve is provided with a cut-away portion 6 and an outwardly tapering orifice 7. By referring to

Fig. 2 it will be apparent that the valve is positioned to permit the fluid to pass from the neck 2 through the orifice 7 and out through the opening 4. Or in other words 60 the valve is turned until the orifice 7 registers with the opening 4 and a round stream, such as is desired for ejecting a fluid at a distance is produced.

It is evident that some means for turning 65 the valve 5 must be provided and for effecting this, the valve is formed at its inner end with a slot 8 which receives a lug 9 carried on a disk 10 mounted on the end of a valve turning stem 11, the latter carrying at its outer 70 end an operating wheel 12. The valve stem 11 passes through a suitable stuffing box 14 threaded into the open end of the nozzle head 3 and forming a bearing for the disk 10 so that the valve is held against longitudinal 75 displacement. It is obvious that by making the valve and the stem separate, the valve is capable of a slight independent movement so that it is readily seated by the pressure of the liquid. A valve of this construction and arrangement is quickly and readily manipulated and it is only necessary to grasp the wheel 12 and turn the same to revolve the valve 5 and produce the desired effect in either a stream or spray. By turning the 80 valve to the position indicated in dotted lines in Fig. 2 the full stream passing through the neck 2 is permitted to pass through the head 3 and out through the opening 4. Should it be desired to entirely shut off the passage of 90 the liquid it is simply necessary to turn the valve to the position indicated in dotted lines in Fig. 2. In Fig. 4 the valve is shown as partly closing the opening 4 which reduces 95 the stream and produces a spray which can be readily varied by slightly turning the valve and decreasing or increasing the size of the opening. In this view the valve 5 is shown in position in full lines for producing a fine spray and in dotted lines for producing a 100 coarse spray. In effecting any of these adjustments or the one previously described it is never necessary to revolve the valve more than one complete revolution.

I desire to call attention to the fact that in 105 use, the valve is conveniently grasped in a substantially vertical position, the stream being ejected at the proper angle on account of the location of the opening 4. The nozzle being grasped in one hand the wheel 12 may 110 be readily turned with the other hand. When it is desired to use the nozzle as a lawn spray

it is laid in a horizontal position with the opening 4 uppermost and the valve properly adjusted as shown in Fig. 6.

It is to be understood that this nozzle may 5 be used in various ways and in ejecting different kinds of liquids under different conditions. Its parts are comparatively few in number and it does not possess internal operating threads or other complicated and expensive constructions likely to get out of order and with the working of which heavy liquids would interfere.

What I claim is:

In a nozzle, a head having an elongated

discharge opening, a valve mounted to turn 15 in the head and having a cut-away portion and an orifice extending through its body at the cut-away portion, and means for registering the cut-away portion or the orifice with the discharge opening.

In testimony whereof I have signed my name to this specification in the presence of 20 two subscribing witnesses.

CHARLES G. HESS.
